CLAIM

The ornamental design for the self-service kiosk, as shown and described.

DESCRIPTION

FIG. 1 is a perspective view of an exemplary self-service kiosk, according to one embodiment of the present disclosure.

FIG. 2 is a front view of an exemplary self-service kiosk, according to one embodiment of the present disclosure.

FIG. 3 is a back view of an exemplary self-service kiosk, according to one embodiment of the present disclosure.

FIG. 4 is a side view of an exemplary self-service kiosk, according to one embodiment of the present disclosure.

FIG. 5 is a side view of an exemplary self-service kiosk, according to one embodiment of the present disclosure.

FIG. 6 is a top view of an exemplary self-service kiosk, according to one embodiment of the present disclosure; and,

FIG. 7 is a bottom view of an exemplary self-service kiosk, according to one embodiment of the present disclosure.

1 Claim, 7 Drawing Sheets
